UNITED STATES PATENT OFFICE

EDWARD N. JACOBI, OF MILWAUKEE, WISCONSIN, ASSIGNOR TO BRIGGS AND STRATTON CORPORATION, OF MILWAUKEE, WISCONSIN, A CORPORATION OF DELAWARE

HANDLE ASSEMBLY

Application filed July 16, 1928. Serial No. 292,961.

This invention relates to certain new and useful improvements in handle assemblies and has as an object the provision of improved and simplified means for mounting handles especially designed for the operation of automotive window regulators, door locks and the like whereby the radial position of the handle on its shaft may be readily adjusted to any angle.

10 A more specific object of this invention resides in the provision of an improved handle assembly in which the handle bore and the shaft are provided with a plurality of interlocking teeth whereby the handle 15 may be readily non-rotatably mounted on the shaft in any radial position.

And a still further object of this invention resides in the provision of an improved handle assembly whereby the handle may 20 be readily engaged on its shaft in any radial position with respect thereto and having means whereby the engagement of the handle over its shaft locks the same thereon.

With the above and other objects in view 25 which will appear as the description proceeds, my invention resides in the novel construction, combination and arrangement of parts substantially as hereinafter described and more particularly defined by the ap- 30 pended claim, it being understood that such changes in the precise embodiment of the hereindisclosed invention may be made as come within the scope of the claims.

In the accompanying drawing, I have illus- 35 trated one complete example of the physical embodiment of my invention constructed according to the best mode I have so far devised for the practical application of the principles thereof, and in which:

40 Figure 1 is a view, partly in section and partly in elevation, of a window handle assembly embodying my invention; and

45 Figure 2 is an enlarged, sectional view, taken transversely through Figure 1 on the plane of the line 2—2.

Referring now more particularly to the accompanying drawing, in which like numerals designate like parts, 5 designates a shaft which, in the present instance, is illustrated as being the operating shaft of a win-

dow regulating mechanism, a portion 6 of which is shown, the shaft having an operating handle or lever member 7 secured on its outer end to impart rotation to the shaft and operate the regulator. The outer end of 55 the shaft has its surface longitudinally serrated to provide a plurality of spaced teeth 8 which are adapted to have a fairly snug fit between correspondingly shaped and spaced longitudinal teeth 9 formed in the 60 wall of bore 10 in a hub or boss 11, on one end of the handle member.

The intermeshed teeth 8 and 9 provide a non-rotatable connection between the handle member and the shaft 7 and also permit comparatively fine radial adjustment of the handle on the shaft making it possible for the automotive manufacturer to adjust all the handle members of the car to the same circumferential position when the windows 70 are closed to maintain uniformity of appearance.

The handle member is secured on the shaft against longitudinal movement by a spring 75 detent in the form of a substantially U or hair-pin shaped spring 12, the end portions of which are curved inwardly and then outwardly, as at 13, to provide inwardly directed detent fingers 14 which project through recesses 15 in the opposite sides of the boss 80 11 in communication with the bore 10 whereby the faces 14 engage in an annular channel or groove 16 formed in the shaft 5.

The boss 11 is grooved or channeled, as at 17, in register with the recesses 15, so that 85 the entire spring is disposed within the plane of its circumference.

The extreme outer end of the shaft 5 is preferably tapered, as at 18, to facilitate the positioning of the handle 7 on the shaft and 90 acts as a cam to spread the detent fingers 14 of the spring as the handle member is engaged over the shaft, the detent fingers snapping into the annular channel 16 as they register therewith, as will be readily apparent. 95 When it is desired to remove the handle 7 for the purpose of repair or replacement of the parts, a tool is inserted in the groove 17 at either end of the spring 12 in order to disengage it.

From the foregoing description, taken in connection with the accompanying drawing, it will be readily apparent to those skilled in the art to which an invention of the character described appertains, that I provide an improved and simplified means for securing the handle member on its shaft and for permitting the adjustment of the handle to any angle.

10 What I claim as my invention is:

In combination with a shaft to be turned, a lever arm for imparting rotation thereto, a boss projecting from one side of the lever arm and having a bore to receive the shaft end, longitudinal serrations in the wall of the bore, longitudinal serrations on the shaft end engageable with the serrations in the lever arm bore to secure the lever arm against rotation with respect to the shaft in any desired position of circumferential adjustment, the shaft end having an annular groove, and the lever arm boss having a groove encircling part of its circumference and opening into the bore at the ends of the groove, and a spring detent lying entirely within the groove formed in the boss with its end portions projected through the openings therein to engage the groove in the shaft, the extreme end of the shaft being tapered so that the end portions of the spring detent are automatically engageable with the shaft groove upon engagement of the lever arm with the shaft end.

In testimony whereof I have hereunto affixed my signature.

EDWARD N. JACOBI.
